UNITED STATES PATENT OFFICE.

JAMES H. ABERCROMBIE, OF NEWARK, NEW JERSEY, ASSIGNOR TO HIMSELF
AND ROBERT B. SYMINGTON, OF SAME PLACE.

MACHINE FOR TREATING INCANDESCENT MANTLES.

SPECIFICATION forming part of Letters Patent No. 639,331, dated December 19, 1899.

Application filed March 21, 1899. Serial No. 709,884. (No model.)

To all whom it may concern:

Be it known that I, JAMES H. ABERCROMBIE, a subject of the Queen of Great Britain, residing in Newark, in the county of Essex and 5 State of New Jersey, have invented a certain new and useful Improvement in Machines for Treating Incandescent Mantles, of which the following is a specification.

The invention relates to the manufacture of 10 mantles of the "Welsbach" type; and its object is to provide means whereby certain steps in the treatment may be performed automatically by machinery, thereby lessening the cost of production and increasing the output and 15 also improving the quality and uniformity of the product. The mantles are mounted in a traveling frame or carrier, and the treating devices move with the mantles during a portion of the travel, returning to accompany 20 and act upon the next succeeding mantle when one has been treated. Means are provided for producing the required changes in relative elevation between the mantle and its treating devices and for engaging and releasing the latter as the mantles are successively subjected to treatment.

The invention also consists in certain details of construction and arrangements of parts to be hereinafter described.

30 The accompanying drawings form a part of this specification and show the manner in which I have carried out the invention.

Figure 1 is a horizontal section or plan view. Fig. 2 is a vertical section through the machine on the line 2 2 in Fig. 1, certain portions being shown in elevation. Fig. 3 is an 35 elevation showing a portion detached. Fig. 4 is an elevation showing a circular portion developed in a plane.

40 For the purposes of this description the process of manufacturing mantles need not be specifically set forth. Many of the steps may be performed on a machine constructed in accordance with this invention, but I will 45 describe the machine as adapted to perform the "dipping" and "trimming" steps, by which are meant, first, the immersion in collodion or other bath containing a strengthening material in solution in a quickly-drying 50 solvent applied to the mantle after the "burning off" and "shaping" have been effected

for the purpose of increasing the body of the delicate structure in order to enable it to withstand the handling to which it is subjected in packing, transportation, and final 55 placing in position in the burner, and, second, the trimming or removal of any surplus length, so that the finished mantles will have the desired uniformity. The latter process is performed after the solvent has evaporated 60 and the mantle strengthened as above.

Similar letters of reference indicate the same parts in all the figures.

A refers to the fixed framework, consisting of a circular bed-plate A', uprights A², and 65 top plate A³, supported thereby, and forming an open cage within which the revolving and other moving parts are mounted.

B is a vertical centrally-located shaft supported in the step A⁴ on the bed-plate and 70 guided in the bearing A⁵ in the top plate. Motion is received through a worm C, driven by a motor (not shown) and worm-wheel B², fixed to the lower end of the shaft below the bed-plate. The shaft, at about the mid-height, 75 carries a series of arms B', joined together by a web or plate to form a spider frame or carrier, equipped at the extremity of each arm with vertical ways B³, in which is mounted a slide D, held against rotation axially, 80 and provided at the upper end with a spring-clamp D' and guiding-eye D² for setting and firmly grasping a mantle-support M' and at the lower end with an arm D⁵, carrying a roller D³, traveling in a cam-groove e in the 85 vertical face of an annular track E, supported on brackets A⁶ from the uprights A². The track or groove is formed with depressions and elevations, as will be described, serving to lower and raise the slide during its circular traverse and correspondingly lower and lift the mantle M, carried by the support M'.

F and G are swinging arms extending radially from a hub H, loosely mounted on the shaft B below the spider-frame and carrying 95 devices for treating the mantles. I have shown the arm F as supporting a small vessel or reservoir F', of collodion or other strengthening material in solution, and the arm G as equipped with mechanism for trimming the 100 skirt of the mantle.

The arms F and G are shown at a right an-

- gle to each other, and both are for convenience joined to the same hub or sleeve H to swing together.
- From the lower end of each slide extends a lateral arm or lug D⁴, which when the mantle is some distance above the vessel F' will pass clear above a fin or web F² on the pedestal F³, but when the slide lowers slightly will engage the fin and compel the pedestal and vessel to travel with the slide by swinging the arm on the shaft B in the direction indicated by the arrow. The engagement takes place while the skirt of the mantle is still above the vessel and the axial line of the latter coincides with that of the former and the roller D³ has started down the incline E' in the track. A further lowering of the slide dips the mantle into the solution, the bight or open loop m on the support allowing the complete submergence when the roller is at the lowest point e'. The parts remain in the same relative position until the mantle is sufficiently impregnated, and the slide rises by ascending the incline E² of the track, lifting the mantle from the vessel and releasing the lug from the fin, thus allowing the arm F and its connections to return to their original position through the influence of a spring or weight. I have shown a stop A⁷ projecting from the framework, in which is mounted a small pulley A⁸ and against which the wing F⁴, extending laterally from the pedestal F³, rests when the arm is not engaged. The parts are held in this position by a weight F⁶ on the end of a cord F⁵ running over the pulley and secured to the wing. The weight is preferably received in a trumpet-mouthed cylinder A⁹, performing the functions of a dash-pot in softening or cushioning the shock of impact at the extreme of the return motion, and thus lessening the danger of spilling the contents of the vessel. It will be understood that any preferred form of govenor may be employed with or substituted for the cushioning device just described. It is important that the return movement be made with but little loss of time and also that the collodion be not wasted by the overflow caused by its sudden arrest.
- The dipped mantle continues its travel idly until sufficient time has elapsed to insure sufficient evaporation of the solvent, leaving the gum or other strengthening material, and is then ready for the trimming operation.
- To hasten the evaporation, I provide means for bathing the mantle during the drying period in currents of air, preferably warmed, received through a pipe R from a blower or other source and escaping below the mantle through the open slot r in the curved pipe or segmental nozzle R'.
- The mechanism for trimming or cutting off the skirt of the mantle to the required length is carried on the standard G' on the arm G.
- It consists of a short tube or ring G², having a flaring mouth and plane lower face, and a revolving cutter-wheel G³, placed in such re-

lation to the plane face as to shear off the lower margin of the skirt when the mantle is lowered within the ring. The cutter-wheel 70 is carried on the long arm of a lever I, mounted on the flange I' of a sleeve I², revolved by a belt J³, running on a pulley I⁴ from a larger pulley J² on a vertical counter-shaft J, driven by a small pulley J' at the lower end, receiving a belt K from a large pulley B⁴ on the shaft B. The shaft J and sleeve I² are supported vertically in bearings in the standard, and the lever I is so proportioned as to bring the cutting edge of the wheel into shearing 80 contact with the lower edge of the ring when the lever is tilted by raising the short arm. This is effected by the movement of a vertical rod L, extending axially through the sleeve. Its pointed upper end is received in 85 a conical recess on the under face of the short arm and its lower end provided with a roller L', resting upon a short segmental section of track N, supported by brackets reaching inward from the fixed work and having a short 90 slightly-raised portion n at about its mid-length. The cutter is held normally out of contact with the ring by the contractile spring I⁵, extending between the flange I' and an arm on the lever, as shown, and the cutter stands 95 just below the ring and concentric thereto, leaving an annular space in which the skirt of the mantle may lower. The arms F and G are so set relatively to each other and to the positions of the slides D that at the time 100 the lug D⁴ strikes the fin and moves the arm F, as described, a mantle, which has been dipped and dried, hangs vertically above the ring G² and in axial line therewith, and by reason of the downward incline E³ in the groove or track 105 E its slide sinks and lowers the skirt within the ring to a distance determined by the difference in level of this portion of the track. While thus inclosed the roller L' reaches the elevation n on the track N, forcing the rod L 110 upward and throwing the revolving cutter G' outward, and thus shearing off that portion of the mantle below the ring. As soon as the elevation n has been passed the cutter returns to its central position, and the mantle is lifted 115 clear of the ring by the upward incline E' in time to allow the arm G to swing idly back to its first position when the arm F is released.

The finished mantles, with their supports M', are removed and untreated ones substituted 120 at the "donning and doffing" station E⁵, between the limit of forward motion reached by the arm G and the backward movement of the arm F. The parts should be so proportioned and the speed so regulated as to allow 125 sufficient time for the change. I have for the purposes of illustration shown only four slides D; but it will be understood that there may be as many more as the size of the spider-frame will accommodate, while allowing sufficient space between for the proper performance of the treatment at each step.

Modifications may also be made in the forms and proportions and in other details of

construction without departing from the principle of the invention or sacrificing its advantages.

Other means than the belts and pulleys shown for driving the cutter may be employed.

The dash-pot A⁹ may be dispensed with or other restraining means substituted.

The angle at which the arms F and G are placed relatively to each other may be varied, and each arm may be mounted upon the central shaft independently of the other. In such case both will be provided with fins F², adapted to be struck by the lugs D⁴, and with means for returning each to its place, as will be understood.

I claim—

1. In a machine for treating mantles, means for supporting the latter and carrying them forward in succession, in combination with means adapted to accompany each of said mantles through a portion of its travel and perform a step in the manufacture, and to return to act similarly with a succeeding mantle, all substantially as herein specified.

2. In a machine for treating mantles, means for supporting the latter and carrying them forward in succession, a device adapted to accompany each of said mantles through a portion of its travel and act upon said mantle to perform a step in the manufacture, and to return to act similarly with a succeeding mantle, and means for varying the relative positions between said mantle and acting device, all combined and arranged to serve substantially as herein specified.

3. In a machine for treating mantles, a series of mantle-carrying slides mounted in a moving frame or carrier with liberty to rise and sink therein, and means for raising and lowering said slides, in combination with means adapted to accompany each of said slides through a portion of its travel and perform a step in the manufacture of its mantle and to automatically return to act similarly with a succeeding slide and mantle, all substantially as herein specified.

4. In a machine for treating mantles, a series of mantle-carrying slides mounted in a moving frame or carrier with liberty to rise and sink therein, and means for raising and lowering said slides, in combination with a liquid-reservoir engaged by one of said slides and moved forward through a portion of the travel of the latter, and means for returning said reservoir when released to be again moved forward by the engagement of a succeeding slide, all substantially as herein specified.

5. In a machine for treating mantles, a series of mantle-carrying slides mounted in a moving frame or carrier with liberty to rise and sink therein, and means for raising and lowering said slides, in combination with means for trimming the skirt of a mantle carried on one of said slides, engaged by the latter and moved through a portion of its travel,

and means for returning the trimming mechanism when released to again move forward with and act upon a succeeding mantle, all substantially as herein specified.

6. A series of mantle-carrying slides mounted in a revolving frame or carrier with liberty to rise and sink therein, and means for raising and lowering said slides, connected arms on the same axis as said frame, arranged to be engaged by one of said slides and moved through a portion of the revolution, in combination with means carried by said arms for simultaneously and automatically performing steps in the manufacture of the mantles carried on said slides, and means for returning said arms when released to again move forward with and act upon succeeding mantles, all substantially as herein specified.

7. The frame or carrier B' and means for revolving it, a series of slides D mounted therein and traveling in a track E having depressions and elevations for lowering and raising said slides, and means on the latter for supporting a series of mantles, in combination with a swinging arm F carrying a liquid-reservoir F', and having the fin F² thereon, a lug D⁴ on each of said slides adapted to engage and release said fin, means for returning said arm when released, and a stop adapted to limit the return movement, all substantially as herein specified.

8. The frame or carrier B' and means for revolving it, a series of slides D mounted therein and traveling in a track E having depressions and elevations for lowering and raising said slides, means on the latter for supporting a series of mantles, in combination with a hub H and its arm F carrying a liquid-reservoir and having the fin F² thereon, a lug D⁴ on each slide adapted to engage and release said fin, means for returning said arm when released, and an arm G fixed to said hub and moving with said arm F, carrying a trimming mechanism arranged to act simultaneously with said reservoir in treating two mantles in the dipping and the trimming steps, all substantially as herein specified.

9. The swinging arm G, the ring G² supported thereon and adapted to receive the skirt of a mantle, the sleeve I² located below said ring and in line therewith, and means for rotating said sleeve, the lever I mounted on said sleeve and carrying the cutter-wheel G³, the rod L arranged axially within said sleeve, and means for moving said rod and thereby tilting said lever to produce a shearing cut by the action of said cutter-wheel with said ring and remove that portion of said skirt below said ring, all combined and arranged to serve with a mantle-carrying device, substantially as herein specified.

10. The revolving frame or carrier B', and central shaft B upon which it is carried, the slides D mounted in said frame and each adapted to support a mantle in position for treatment, the track E, e supporting said

slides and having depressions and elevations whereby said slides are lowered and raised as required during their traverse, the swinging arm G, the ring G² supported thereon and 5 adapted to receive successively the skirts of the mantles carried by said slides, the sleeve I² located below said ring and in line therewith, the lever I mounted on said sleeve and carrying the cutter-wheel G³, the rod L ar-
10 ranged axially within said sleeve, the track N in the path of said rod adapted to raise and lower the latter and thereby tilt said lever to produce a shearing contact between said wheel and ring, the pulley I⁴ on said sleeve, the counter-shaft J carried by said swinging arm and having the pulleys J' J², the pulley B⁴ on said central shaft, and the belts J³ and K running on the several pulleys and adapt-
15 ed to transmit motion to said sleeve and its
20 connections from said central shaft, all combined and arranged to serve substantially as herein specified.

11. The frame or carrier B' and means for

revolving it, a series of slides D mounted therein with liberty to rise and sink therein 25 and traveling in a track E having depressions and elevations for lowering and raising said slides, and means on the latter for supporting a series of mantles, in combination with a swinging arm F carrying a liquid-reservoir 30 F', and having the fin F² and wing F⁴ thereon, a lug D⁴ on each of said slides adapted to engage and release said fin, means for returning said arm when released, a stop arranged in the path of said wing and serving with 35 the latter to limit the return movement, and means as the pipe R and nozzle R' for supplying a current for drying said mantles, all sub-stantially as herein specified.

In testimony that I claim the invention above set forth I affix my signature in presence of two witnesses.

JAMES H. ABERCROMBIE.
